UNITED STATES PATENT OFFICE.

EDWARD W. BURGESS, OF CHICAGO, ILLINOIS, ASSIGNEE, BY MESNE ASSIGNMENTS,
TO INTERNATIONAL HARVESTER COMPANY, A CORPORATION OF NEW JERSEY.

SILO-PACKER.

1,354,280.

Specification of Letters Patent. Patented Sept. 28, 1920.

Application filed April 6, 1914. Serial No. 829,866.

To all whom it may concern:

Be it known that I, EDWARD W. BURGESS, a citizen of the United States, residing at Chicago, in the county of Cook and State 5 of Illinois, have invented certain new and useful Improvements in Silo-Packers, of which the following is a full, clear, and exact specification.

My invention relates to silos, and in particular to mechanism for automatically packing the material as it is delivered to the silo. The operation of packing the silage in the silo has heretofore been accomplished by placing two or more men within 10 the silo and tramping the silage as it was delivered thereto. This operation was an extremely disagreeable and arduous one and much loss of silage resulted from insufficient packing. The object of this invention is to provide a mechanism which 15 will automatically and effectively pack the material, and one adjustable to silos having different diameters and not requiring any contact with the body of the silo to permit 20 the operation of the mechanism. The invention consists in certain novel features 25 of construction, combination and arrangement of parts, as will be more fully described and particularly pointed out in the 30 appended claims.

In the drawings—

Figure 1 is a top plan view of a packer having my invention embodied in its construction;

Fig. 2 is a side elevation of Fig. 1;

Fig. 3 is a vertical section of a silo designed to illustrate the manner of operating the packing mechanism;

Fig. 4 is a cross section of Fig. 1 on an 40 enlarged scale and along line A—B; and

Fig. 5 is a cross section of Fig. 1 on an enlarged scale and along C—D.

Referring to the drawings, wherein the same reference numerals designate like 45 parts throughout the several views, a common form of circular silo is represented by 1, and it may be of metal, wood, cement or other construction, having substantially smooth and symmetrical inside walls, 2 50 represents the packer, including two U-shaped sections 3, alike in form and having slotted inner ends that overlap each other at the middle of the packer, whereby the packer is adjustable in length to meet the 55 requirements of operation in silos having

different diameters. The sections are secured together by means of a centrally disposed bolt 4 received by the slotted ends of the packer sections and a spacing pipe section 5 between the overlapping ends of 60 the packer sections, and a short thimble section 6 at the upper side of the packer that is received by a vertical opening in a U-shaped yoke member 7, in which is journaled a crank carrying shaft 8, 65 having a winding drum 9 secured thereto, and 10 represents a pawl member pivotally mounted upon one of the vertically disposed arms of the yoke and adapted to engage with a toothed flange 11 integral with the 70 winding drum in a manner to secure the drum against rotation in one direction, the yoke being permitted to turn freely about the thimble section 6 when the packer is rotated during its operation. 12 represents 75 vertically disposed shafts journaled in bearing members 13 secured to the outside ends of the packer sections 3, the shafts being provided with laterally extending arms 14 at opposite ends thereof, and preferably integral therewith, upon which are journaled 80 guide wheels 15 adapted to roll upon the adjacent wall of the silo as the packer rises and falls in its operation. 16 represents torsional springs carried by the shafts 12 85 and operative between a fixed part of the packer sections and one of the arms 14 in a manner to yieldingly hold the guide wheels 15 in engagement with the wall of the silo and permit them to accommodate themselves 90 to any irregular contour of the surface of the wall. 17 represents sectors, preferably made of wood, and secured to the bottom members of the packer sections 3 by means of strap members 18, upon the 95 opposite sides of the longitudinal center of the packer, and 19 represents brace members having their lower ends secured to the outside ends of the straps 18 and their upper ends to the upper members of the 100 packer sections 3. 20 represents a sheave disposed centrally of the silo, at its top, and 21 a second sheave disposed outside of the wall of the silo at its upper end. 22 represents a common form of hoisting jack 105 outside of the silo, including a rotatable pulley 23 that may derive motion from any source of power, as by means of a driving belt 24. 25 represents a freely swinging arm journaled coaxially with the pulley 23, 110

and 26 a pin carried by the pulley and engaging with the arm during half a revolution of the pulley, and to permit the arm to swing about its axis independent of the 5 pin during the remaining half of the revolution of the pulley in a well-known way. 27 represents a tension spring having one end secured to the free end of the arm 25 and its opposite end to one end of a hoisting rope 28 that leads upward over the sheaves 21 and 20, and then downward within the silo to the packer, and connected with the winding drum 9.

In operation the dimensions of the packer 15 are such as will readily permit it to be passed through the door opening in the wall of the silo. The sections are then adjusted longitudinally so that the packer may be moved freely up or down along the walls 20 of the silo and rotated therein. The hoisting rope is adjusted upon the winding drum in a manner permitting the packer to descend to the desired plane, and when motion is imparted to the pulley 23 the arm 25 alternately pulls down upon the hoisting 25 rope and releases it in a manner to lift the packer a predetermined height and permit it to descend by gravity upon the material in a step by step rotative movement, and 30 the operator adjusts the winding drum to take up the slack in the hoisting rope and as the silo is gradually filled.

Having shown one embodiment of my invention in its preferred form, it is understood that various changes in form, proportions and manner of operation may be made without departing from the principle or spirit of the invention.

What I claim as my invention, and desire to secure by Letters Patent, is:

1. A silo packer adapted to have a rising and falling movement within a silo, and means whereby the packer may be slidably adjusted for use in silos having different diameters.

2. A silo packer having sections and adapted to have a rising and falling and a rotative movement within the walls of the silo, and means whereby the packer sections 50 may be slidably adjusted upon each other to adapt said packer for use in silos having different diameters.

3. A silo packer adapted to have a rising and falling movement within the walls of the silo, said packer including diametrically disposed U-shaped sections having their inner ends overlapping each other and adjustably secured together whereby the packer may be extended or contracted longitudinally.

4. A silo packer adapted to have a rising and falling movement within the walls of the silo, said packer including a pair of diametrically disposed U-shaped sections having their inner ends slotted longitudi-

nally, a spacing member disposed between the inner ends of said sections, and a centrally disposed bolt received by the slots in said sections and clamping the two sections in adjusted relation.

5. A silo packer adapted to have a rising and falling movement within the walls of the silo, said packer including a pair of diametrically disposed sections adjustable longitudinally upon each other, and a winding 75 drum swivelly connected with said packer at its middle.

6. A silo packer adapted to have a rising and falling movement within the walls of the silo, said packer including a pair of diametrically disposed U-shaped sections having their inner ends overlapping and adjustable longitudinally upon each other, spacing pipes disposed between the inner ends of said sections, a yoke member having a winding drum movable therein, a through bolt received by an opening in said yoke and said spacing pipe and securing said packer sections in adjusted relation, said yoke being permitted to turn freely 85 about the axis of said bolt.

7. A silo packer having packing members and adapted to have a rising and a falling movement within the walls of the silo, and guide members carried by and movable with 95 said packing members and adapted to engage with the walls of the silo.

8. A silo packer adapted to have a rising and falling movement within the walls of the silo and disposed diametrically thereof, 100 guides carried by said packer and yieldingly held in engagement with the walls of the silo.

9. A silo packer adapted to have a rising and falling movement within the walls of 105 the silo and disposed diametrically thereof, guide wheels carried by opposite ends of said packer and engaging with the walls of the silo, said wheels being movable toward and from the walls and yieldingly held in 110 engagement therewith.

10. A silo packer adapted to have a rising and falling movement within the walls of the silo and disposed diametrically thereof, arms pivotally mounted upon opposite 115 ends of said packer and movable toward and from the walls of the silo, guide wheels journaled upon said arms, and springs operative to swing said arms in a direction to hold said wheels in contact with the walls 120 of the silo.

11. A silo packer adapted to have a rising and falling movement within the walls of the silo and disposed diametrically thereof, vertically disposed shafts journaled in 125 bearings secured to the opposite ends of said packer and having laterally extending arms at opposite ends thereof, guide wheels journaled upon said arms, and torsional springs encircling said shafts and operative to yield- 130

ingly hold said wheels in contact with the walls of the silo.

12. A silo packer adapted to have a rising and falling movement within the walls of the silo, said packer including a pair of **U**-shaped sections diametrically disposed and having their inner ends overlapping each other and adjustably secured together, sectors secured to each of the lower members 10 of said sections and disposed upon opposite sides of the longitudinal center of said section members whereby said sections may be adjusted longitudinally upon each other.

13. A silo packer adapted to move within 15 a silo and having rigid radially extensible members for increasing its packing area.

14. A silo packer having packing sections and adapted to move vertically and hori-

zontally within the silo, and guiding means carried by and movable with said packing 20 sections and extending laterally therefrom.

15. A silo packer adapted to move within a silo, and having rotatable guiding means therefor carried by and movable with said packer and contacting with the walls of the 25 silo.

16. A silo packer adapted to move within a silo, and having yielding means for guiding purposes.

In testimony whereof I affix my signature, 30 in the presence of two witnesses.

EDWARD W. BURGESS.
